CASE FOR WATCHMAN'S CLOCK

Harold E. Hobby, Gardner, Mass., assignor to
Simplex Time Recorder Co., Gardner, Mass., a
corporation of Massachusetts

Application June 10, 1949, Serial No. 3,196

Term of patent 14 years

(Cl. D42—7)

To all whom it may concern:

Be it known that I, Harold E. Hobby, a citizen of the United States, residing at Gardner, in the county of Worcester and State of Massachusetts, have invented a new, original, and ornamental Design for Case for Watchman's Clock, of which the following is a specification, reference being had to the accompanying drawing, forming part thereof.

Fig. 1 is a front elevational view of a case for watchman's clock, showing my new design;

Figs. 2 and 3 are side elevational views of opposite sides thereof;

Fig. 4 is a top plan view thereof;

Fig. 5 is a bottom view of the case for a watchman's clock.

The essential features of my design reside in

the parts shown in full lines, the fragments of the carrying strap shown in Figs. 1, 2, 3, and 4 being for illustrative purposes only.

I claim:

The ornamental design for a case for watchman's clock, as shown.

HAROLD E. HOBBY.
